[57]

CLAIM

The ornamental design for the handleset, as shown and described.

DESCRIPTION

FIG. 1 is an oblique view of a handleset, the milk pitcher handle shown in broken lines forms no part of the claimed design;

FIG. 2 is an enlarged left side view of FIG. 1, the right side being a mirror image;

FIG. 3 is a front view of FIG. 2;

FIGS. 4 and 5 are top and bottom views of FIG. 2, respectively;

FIG. 6 is an enlarged front view of the circled area in FIG. 3; and,

FIG. 7 is a cross sectional view taken on line 7—7 of FIG. 6.
